UNITED STATES PATENT OFFICE

140,761

DESIGN FOR A COMBINED DRAWER PULL AND ESCUTCHEONS

Earl M. Borchers, Rockford, Ill., assignor to
American Cabinet Hardware Corporation,
Rockford, Ill., a corporation of Illinois

Application August 2, 1944, Serial No. 114,696

Term of patent 7 years

(Cl. D10—8)

To all whom it may concern:

Be it known that I, Earl M. Borchers, a citizen
of the United States, residing at Rockford, in the
county of Winnebago and State of Illinois, have
invented a new, original, and ornamental Design
for a Combined Drawer Pull and Escutcheons, of
which the following is a specification, reference
being had to the accompanying drawing, forming
a part thereof.

Figure 1 is a front elevational view of a com-
bined drawer pull and escutcheons showing my
new design.

Fig. 2 is a perspective view thereof.

Fig. 3 is a side elevational view, and

Fig. 4 is a front elevational view of the drawer
pull shown in Figs. 1, 2, and 3, the escutcheons
being omitted.

I claim:

The ornamental design for a combined drawer
pull and escutcheons, substantially as shown.

EARL M. BORCHERS.
